UNITED STATES PATENT OFFICE.

CHARLES L'ENFANT, OF NEW YORK, N. Y.

CARD CASE.

Application filed August 11, 1926. Serial No. 128,605.

The present invention relates to card cases, and more particularly to that type adapted to display cards, licenses, or other papers which are to be carried and which require protection against handling, dust and the like.

An object of the present invention is to provide a card case of simple and economical construction which is capable of protecting and carrying a number of cards, and in which space is conserved, so that a number of cards may be carried in a relatively small device and which at the same time maintains the cards for easy access when inspection is desired.

The invention also aims at the provision of an improved flexible frame peculiarly constructed for supporting therein transparent panels or side portions to provide pockets in which may be placed the cards and which admits of the inspection of the entire opposite sides of the cards.

Another object of the invention is to provide a structure for card case which admits of the use of a plurality of the same which may be secured together in book form, so that a number of cards may be carried, protected and be ready for inspection as regards their opposite sides without removing the cards from the case or adjusting any of the parts of the case.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of a card case made up of a plurality of sections constructed according to the present invention.

Figure 2 is a plan view of the flexible frame or blank for the frame showing the position of the transparent panes forming one side of each of two pockets, the panes being in position to be secured in the frame.

Figure 3 is a longitudinal section through the structure of Figure 2, taken on the line 3—3 of Figure 2 and showing the transparent panes in position on the frame.

Figure 4 is a plan view of the card case in open position and completely constructed.

Figure 5 is a transverse section taken through the complete card case of Figure 4

on the line 5—5 of Figure 4, parts of the card case being broken away and the section being enlarged.

Figure 6 is a plan view of a slightly modified form of blank or frame of the card case, the broken lines showing the positions of the transparent panes to be located on opposite sides of the body frame or blank.

Figure 7 is a plan view of the card case of Figure 6 completed and ready to receive cards.

Figure 8 is an enlarged transverse section taken on the line 8—8 of Figure 7, and partly broken away, showing the position of the transparent panes or sides with the flexible frame arranged between them.

Figure 9 is a plan view of another modified form of blank or frame for the card case, the broken lines showing the locations of the transparent panes adapted to be secured in the frame.

Figure 10 is a plan view of the card case of Figure 9 in open position and completed ready to receive cards, and

Figure 11 is an enlarged transverse section taken on the line 11—11 in Figure 10 and partly broken away.

Referring first to Figures 2 to 5, inclusive, the card case comprises a body frame 15, which is of any suitable configuration but which in the present instance is of general rectangular shape and which is adapted to be folded over upon itself to provide end portions of equal length providing a pair of leaves. The frame 15 has a central hinge portion 16 which extends from edge to edge across the body frame and which is adapted to be creased or folded over to support the leaves. Each leaf is provided with an elongated central opening 17 adapted to be closed by a backing sheet 18 of celluloid or other suitable transparent material of sufficient size to partially overlap the marginal edge portion of the adjacent opening 17, and which is of less width than that of the body frame 15 to leave a marginal edge portion 19 of the body frame to be turned over for securing the backing sheet 18 to the leaf. The marginal edge portion 19 of the frame 15 provides a flap which extends lengthwise of the body frame or blank, and there is a flap 19 at each longitudinal side of the body frame. Each end of the body frame 15 is provided with a flap 20, which extends beyond the adjacent end of the

110

backing sheet 18 and is adapted to be turned over to hold the backing sheet in place.

A reinforcing hinge strip 21 is superposed upon the hinge strip 16 of the frame and forms part of the frame, and is of sufficient width to slightly overlap the adjacent inner edges of the backing sheets 18 to hold the latter in place, as shown in Figures 4 and 5.

10 The pockets in the leaves are formed by superposing transparent frames or facing sheets 22 upon the backing sheets 18. The flaps 19 and 20 are turned over upon these superposed sheets 18 and 22 to hold the 15 same together, as clearly shown in Figure 5. The facing sheets 22 are of less length than the backing sheets 18, so as to dispose the inner edges of the facing sheets in proximity to the opposite edges of the reinforcing hinge strip 21. The facing sheets 22 are provided with finger notches or recesses 23 in their inner edges to facilitate the drawing or bulging outwardly of the facing sheets 22 for the introduction of a card or the like 25 in the pocket thus formed.

As shown in Figure 1, a plurality of these card cases, as shown in Figure 4 may be placed one within the other and the hinge portions may be secured together by one or 30 more lines of stitches 24 to form a book. The card or sheet which is placed in the pocket of one of the leaves may be inspected at its opposite sides through the backing sheet 18 and the facing sheet 22 without re- 35 moving the card from the pocket or otherwise disturbing the position of the card.

Another preferred form of the invention is disclosed in Figures 6, 7 and 8. In this form of invention the frame or blank which 40 comprises the body portion of the card case may be of substantially rectangular form and cut to provide a rectangular frame 25 adapted to be folded over intermediate its ends to provide a pair of leaves. The frame 45 is provided with an integral hinge portion 26 extending across the frame between its ends and this hinge portion 26 is integral with intermediate or partition sheets 27 composing the intermediate portion of the 50 frame 25, which is cut from the marginal portion of the frame. These sheets 27 are connected only to the hinge strip 26 for a purpose which will subsequently appear.

55 Superposed upon one side of the rectangular frame 25 is a pair of facing transparent sheets 28 and 29 adapted to be secured to the frame 25 by overturning the marginal edge of the frame upon the superposed sheets 28 and 29. This structure is shown 60 in Figures 7 and 8. The partition sheets 27 are located between the facing sheets 28 and 29 as shown in Figure 8, particularly, and the partition sheets 27, therefore, provide separate pockets one at each side thereof in each leaf of the case. These facing sheets

28 and 29 are provided with finger recesses 30 to facilitate the separation or bulging out of the facing sheets 28 and 29 when it is desired to insert a card or the like in the pocket. It will be noted that the facing 70 sheets 28 and 29 are spaced apart at their inner edges so as to lie at opposite sides of the hinge line 31 of the frame. The partition sheets 27 are free at their opposite side and outer end edges, so that the facing 75 sheets 28 and 29 may be placed against opposite sides of the partition sheet 27 and at the same time the facing sheets at their marginal edge portions may be secured together, beneath the over-turned edges of the 80 frame 25.

The form shown in Figures 9, 10 and 11 is substantially the same as the form shown in Figures 6, 7 and 8, with the exception that the partition sheets 27 are shortened or 85 cut off, so as to provide merely partition tongues 32 adapted to project into the pockets formed between the facing sheets 28 and 29 so that cards or the like may be slipped into the pockets from either side of the card 90 case and be held apart at their inner edges by the partition strips 32.

It will be observed that in all forms of the invention the frame may be flexible and is provided with a marginal edge portion 95 adapted to secure the transparent sides in superposed relation so as to provide a pocket between these transparent sides. The use of the partition members, whether the sheets 27 or the strips 32, sub-divides the pockets each 100 into two pockets accessible from opposite sides of the card case, so that each pocket may carry 2 cards in position with back to back where it is necessary only to inspect one side of the card. Of course, in the construction shown in Figures 9, 10 and 11, the card 105 may be inserted from either side of the card case and unless two cards are placed in the same pocket, a single card may be inspected on its opposite sides from the opposite sides 110 of the card case.

I have illustrated and described a preferred and satisfactory embodiment of my invention, but it is obvious that changes may be made therein within the spirit and scope 115 thereof as defined in the appended claims.

What is claimed is:—

1. A card case comprising an elongated body blank foldable intermediately upon its- 120 self to provide a pair of leaves and a hinge portion between the leaves, each leaf having a central opening therein, a pair of transparent sheets disposed one upon the other and over the opening in each leaf, and means integral with the marginal edge portions of 125 each leaf to embrace the edges of each pair of sheets and form a pocket in each leaf adapted to receive a card.

2. A card case comprising a flexible frame over-turned intermediately upon itself to 130

provide a pair of leaves with a connecting hinge strip, each leaf having an intermediate opening and an overturned outer marginal edge portion, and a pair of transparent panes disposed in superposed relation over the opening in each leaf and with their edge portions lying beneath said overturned outer edge portion of the leaf, the inner ends of said pairs of transparent panes terminating at said hinge strip and being free for inserting objects between the panes of each pair.

3. A card case comprising a frame formed of a single piece of material and foldable upon itself to provide a pair of leaves, each leaf having a central opening therein and an integral over-turned outer marginal portion, a pair of transparent panes arranged in superposed relation upon each leaf and beneath the over-turned marginal portion thereof and means securing the edges of the transparent panes together and holding the over-turned marginal portions in place thereon.

4. A card case comprising a frame foldable upon itself to provide a pair of leaves

and a hinge portion connecting the leaves, 25 each leaf of the frame having a central opening therethrough, a pair of transparent sheets placed against each leaf over one face thereof to cover the opening therein, the marginal edge portions of the frame being 30 over-turned upon said pairs of sheets to secure the same together and to the leaves at the marginal edge portions of the sheets, a reinforcing hinge strip secured over said hinge portion of the frame and adapted to 35 overlap the inner end of the transparent sheet of each pair lying adjacent to its respective leaf, the other transparent sheet of each pair terminating at the lateral edge of the reinforcing hinge strip and provided 40 with a thumb notch to facilitate separation of the transparent sheets and introduction of articles therebetween.

In testimony that I claim the foregoing as my invention, I have signed my name 45 hereto.

CHARLES L'ENFANT.
